UNITED STATES PATENT OFFICE.

LUDWIG SCHREINER, OF OEHDE, NEAR BARMEN, GERMANY, ASSIGNOR TO THE FIRM OF J. P. BEMBERG, AKTIENGESELLSCHAFT, OF BARMEN-RITTERSHAUSEN, GERMANY.

PROCESS FOR IMPARTING LUSTER TO YARNS, FABRIC, AND THE LIKE.

1,020,117.

Specification of Letters Patent.

Patented Mar. 12, 1912.

No Drawing.

Application filed December 21, 1909. Serial No. 534,353.

To all whom it may concern:

Be it known that I, LUDWIG SCHREINER, a subject of the German Emperor, residing at Oehde, near Barmen, Germany, have invented a new and useful Process for Imparting Luster to Yarns, Fabric, and the Like; and I do hereby declare the following to be a full, clear, and exact description of the same.

10 This invention relates to an improved process for imparting luster to yarns, fabrics and the like.

15 The invention consists in making the goods quite wet and then calendering them under high pressure, at a high temperature, and with such a high speed that the goods are still wet after the calendering.

20 It is known to produce a brilliant and fairly lasting luster by moistening and calendering goods under high pressure, at a high temperature so that the goods are dried by the calendering process. The present invention differs from such known process by making the goods not only moist but 25 quite wet and by accelerating the calendering process so that the goods are not dried, but are still moist or wet after being calendered. It is furthermore known to pass wet goods around a steam-heated cylinder; but, 30 hereby, a lasting or permanent luster cannot be obtained. The present invention differs from this by the fact that the temperature used in calendering the goods, must be at least so high that the well known Leydenfrost's phenomenon takes place, *i. e.*, that the water, in contact with the heated surface of the rollers used for calendering the goods, does not evaporate at once, but forms 35 spheres separated from the heated surface 40 of said roller by a thin layer or coat of steam which retards the further evaporation of the water.

45 By the present invention, the following advantages are obtained: a higher and more permanent luster and a peculiar silver-like glittering character of such luster. Furthermore, the goods are better protected against the burning effect of the heated roller used for calendering them, and against 50 the oxidizing effect of the air on the hot goods, so that much higher temperature can be used in calendering the goods than heretofore. The base and impermanent parts of the luster are removed in one operation with-

out any special subsequent damping being 55 required. The goods treated according to the present invention can be dyed after calendering them, and hereby obtain a much more uniform color than with the known processes for producing high luster on 60 goods by calendering them.

In order to provide the yarns and the like with permanent luster on both sides, they are passed through two calendering machines in series one after the other; the steel 65 roller of one calender lies beneath and that of the other on top. In order to raise the flattened shape the yarns can, if desired, be subsequently soaked in hot water.

Instead of employing simple pressure, the 70 latter may be combined with friction, *e. g.* by different speeds of the two rollers, placing them obliquely and so on. In a similar way to yarns, other products consisting of vegetable threads can also be treated, such 75 as woven goods, fabrics, etc., for which as a rule treatment on one side is sufficient. Any kind of roller *e. g.* polished, engraved, and so on, may be employed as the pressure roller.

80 The above process can be employed upon both mercerized and non-mercerized fabrics.

What I claim as my invention and desire to secure by Letters Patent is:

1. A process for imparting permanent 85 luster to fabrics or the like made from vegetable fibers, consisting in making the goods quite wet, and then calendering them under high pressure, at so high a temperature as to produce Leydenfrost's phenomenon be- 90 tween the surfaces of the calendering agent and the moist goods, and with so high a speed that the goods are still moist after calendering them.

2. A process for imparting permanent 95 luster to fabrics or the like made from vegetable fibers, consisting in making the goods quite wet, and then calendering them with friction under high pressure, at so high a temperature as to produce Leydenfrost's 100 phenomenon between the surfaces of the calendering agent and the moist goods, and with so high a speed that the goods are still moist after calendering them.

3. A process for imparting permanent 105 luster to fabrics or the like made from vegetable fibers, consisting in making the goods quite wet, and then calendering and em-

bossing them under high pressure, at so high a temperature as to produce Leydenfrost's phenomenon between the surfaces of the calendering agent and the moist goods, and 5 with so high a speed that the goods are still moist after calendering and embossing them.

4. A process for imparting permanent luster to fabrics or the like made from vegetable fibers, consisting in making the goods 10 quite wet, and then calendering and embossing them with friction under high pressure, at so high a temperature as to produce Ley-

denfrost's phenomenon between the surfaces of the calendering agent and the moist goods, and with so high a speed that the 15 goods are still moist after calendering and embossing them.

In testimony whereof, I have signed my name to this specification in the presence of two subscribing witnesses.

LUDWIG SCHREINER. [L. s.]
